(57) **CLAIM**

The ornamental design for a tubing connector for a breastmilk system, as shown and described.

DESCRIPTION

FIG. 1 is a perspective view of a tubing connector for a breastmilk system of the present invention;

FIG. 2 is a top view of the tubing connector for a breastmilk system illustrated in FIG. 1;

FIG. 3 is a front view of the tubing connector for a breastmilk system illustrated in FIG. 1, a rear view being a mirror image thereof; and,

FIG. 4 is a bottom view of the tubing connector for a breastmilk system illustrated in FIG. 1.

The broken lines in the drawing figures form no part of the claimed design. The tubing connector is shown with a symbolic break in its length. The appearance of any portion of the article between the break lines forms no part of the claimed design.
